UNITED STATES PATENT OFFICE

2,612,026

REFRIGERATOR DEFROSTING SYSTEM

William L. Hansen and Harry G. Manson, Princeton, Ind., assignors to Hansen Manufacturing Company, Princeton, Ind., a corporation of Indiana

Application November 10, 1949, Serial No. 126,634

6 Claims. (Cl. 62—4)

1

This invention relates to a defrosting system adapted to both domestic and industrial refrigerators. More particularly still, this invention relates to a refrigeration system including a defrosting unit, and to a cycle of operation for maintaining a refrigerator defrosted.

A refrigerator, either domestic or industrial, includes an evaporator, coils, or some other similar unit through which refrigerant is passed in order to chill the surface of the unit and thereby bring about an exchange of heat between the unit and the enclosure being refrigerated. Due to the fact that there is nearly always considerable moisture in the atmosphere of the enclosure being refrigerated, the evaporator or coils tend to frost up and to accumulate a layer of ice which materially inhibits the refrigerating action, because ice is a relatively effective heat insulator.

It is customary in the art of operating refrigerators periodically to defrost the evaporator to remove the ice therefrom, and thus to restore it to efficient operating conditions. Some refrigerators require that this operation be performed manually, while others are automatic and bring about the defrosting of the evaporator at intervals, say, once every twenty-four hours.

In connection with the automatic defrosting arrangements, it is customary merely to interrupt the operation of the compressor or refrigeration unit so that the evaporator will become warm, due to the lack of supply of refrigerant thereto and permit the ice gradually to melt off. Inasmuch as this normally requires some hours, even if carried out once a day, it is a disadvantage in that the refrigerator has a tendency to warm up throughout, and this is never a desirable occurrence, and sometimes cannot be permitted at all.

Furthermore, under these conditions, a continuous twenty-four hour period of operation of the refrigerator will cause sufficient accumulation of frost and ice on the evaporator or coils that the efficiency thereof is severely impaired.

The particular object of the present invention is to provide an arrangement whereby the evaporator or coils of a refrigerator is maintained substantially free of ice at all times.

Another object is to provide an arrangement in connection with a refrigerator which maintains it at maximum operating efficiency at all times.

A still further object of this invention is to provide an automatic defrosting arrangement for a refrigerator which is inexpensive to con-

2

struct and which can readily be applied to conventional refrigerator structures.

A still further object is to provide an automatic defrosting arrangement which is readily adaptable to any type of refrigerator and refrigerating system.

These and other objects and advantages will become more apparent upon reference to the following description taken in connection with the accompanying drawings, in which:

Figure 1 is a perspective view showing an evaporator of the type commonly employed in connection with domestic refrigerators and including a defrosting heater according to my invention;

Figure 2 is a diagrammatic view illustrating the wiring diagram associated with this invention;

Figures 3 and 4 are views showing the correlation of the timer operated cams which control the switches of the control circuit of Figure 2; and

Figure 5 is a perspective view showing a typical time arrangement for supplying the cams of Figures 3 and 4.

Referring to the drawings, Figure 1 illustrates an evaporator unit 10 which it will be understood is merely exemplary of a number of different types of arrangements that could be employed for providing a refrigerated surface to effect a heat exchange between the refrigerant and the zone being refrigerated. The evaporator shown in Figure 1 is one type encountered in a number of conventional domestic refrigerators.

Refrigerant from the refrigeration unit is supplied to the evaporator 10 through conduit 12, and the evaporated refrigerant is withdrawn from evaporator 10 through conduit 14, returning via this conduit to the refrigeration unit for again being compressed.

Associated with evaporator 10, according to this invention, is a heater element 16 which is preferably an electric unit so as to be readily controllable. The heating element 16 is shown as comprising a relatively thin member mounted on or integral with the side wall of evaporator 10. It will be understood that a number of different manners of associating the evaporator 10 and the heating element 16 could be employed, and that the essential thing is that the heating element 16 is so situated that, when it is energized, it will bring about melting of the frost and ice which accumulates on evaporator 10 during a refrigerating cycle thereof.

It will also be understood that heating element 16 could extend over whatever portion of the outer surface of evaporator 10 it was found desirable to heat, or that there could be a plurality of the elements 16, as, for example, one on each side of the evaporator.

According to this invention, the refrigeration unit and the heating element are alternately energized, so that at no time is there any substantial accumulation of ice or frost on the surface of the evaporator. One manner of controlling the energization of the refrigeration unit and heating element is illustrated in Figure 2.

In Figure 2 the drive motor for the refrigeration unit is indicated at 18, and it will be seen to be connected between the power lines L1 and L2 in series with a switch S2 and thermostatic switch mechanism 20. Heating element 16 has one side thereof connected to line L2 and the other side thereof connected to a terminal 22 of switch S2.

In one position S2 establishes a circuit from line L1 to thermostatic switch 20, and in its other position, it interrupts the circuit to the thermostatic switch and closes on contact 22 to bring about energization of heating element 16.

In order to provide for the alternate energization of drive motor 18 and heating element 16 according to a predetermined timed cycle, there is provided a timer motor 24 which has one side connected with power line L2 and its other side connected with a movable blade of a switch S1. Switch S1 has a first position where it closes on contact 26 that is connected with the drive motor side of thermostatic switch 20. The said switch also has a second contact 28 that is connected with line L1.

Switches S1 and S2 are normally urged toward their second positions and are adapted for being moved toward their first said positions by cams mounted on the output shaft of the timer motor 24. These cam arrangements are shown in Figures 3 and 4.

Figure 3 shows that there is a cam at 30 for controlling switch S1. The cam comprises the recess 32 which permits switch S1 to rest in its second position for a predetermined length of time that cam 30 is rotated. Cam 30 comprises the raised part 34, and this portion of the cam holds switch S1 in its first position for a predetermined length of time.

The cam for controlling switch S2 is indicated at 36, and this cam also comprises a recess 38 and a raised part 40, the said recess being effective for permitting switch S2 to move to its second position with the raised part being effective for moving the said switch to its first position.

The cams 30 and 36 are mounted on the drive shaft 42 of timer motor 34 and are fixedly oriented thereon to obtain a predetermined sequence of operation. Reference to Figures 3 and 4 will reveal that recess 32 has a greater circumferential extent than recess 38, and that cams 30 and 36 are so aligned that switch S1 is permitted to move into its second position where its blade closes on contact 28 prior to movement of S2 into position where its blade closes on contact 22.

Further, cam 36 moves switch S2 out of engagement with contact 22 prior to movement of switch S1 out of engagement with contact 28. It will be apparent that the entire period of actuation of switch S2 into its second position takes place within the limits of the period that switch S1 is in its second position.

Returning for the moment to Figure 2, the thermostatic switch element 20 shown therein may be considered to comprise any of the control means normally employed in connection with refrigerators for initiating operation of the drive motor of the refrigeration unit. For example, element 20 could comprise a simple thermostatically operated switch so arranged as to be directly responsive to the temperature of the enclosure being refrigerated, so that, when the temperature of the said enclosure reached a predetermined amount, a refrigeration cycle would be automatically initiated.

Element 20 could also comprise means responsive to the temperature at the surface of the evaporator, this arrangement commonly being employed in connection with domestic refrigerators.

In connection with a number of refrigeration systems, the refrigerator unit includes a compressor and receiver, and when the refrigeration unit operates, it compresses the refrigerating medium and delivers it in the form of a liquid to the receiver. Thereafter the liquid refrigerant is conveyed to the evaporator and admitted thereto under the control of a float valve or thermostatically controlled valve to cause chilling of the said evaporator.

With an arrangement of this nature the control of the drive motor 18 could comprise a pressure responsive element that initiated operation of the said unit when the supply of refrigerant in the receiver reached a predetermined minimum value, and interrupted operation of the said unit when the supply of refrigerant in the receiver again reached a predetermined value.

It will, accordingly, be understood that the element 20 is not to be considered as limited to a simple thermostatic switching element, but may comprise any suitable system for periodically initiating operation of the drive motor of the refrigeration unit in response to a stimulus indicating the need for a supply of compressed refrigerant into the refrigerating system.

In operation, assuming the element 20 to be open so that drive motor 18 is de-energized, cams 30 and 36 will occupy substantially the positions in which they are illustrated in Figure 5. In these positions the cams hold switches S1 and S2 in the positions in which they are illustrated in Figure 2. Inasmuch as element 20 is open, timer motor 24 is de-energized.

When element 20 closes, indicating the need for operation of the refrigeration unit to supply refrigerant to the system, timer motor 20 becomes energized simultaneously with drive motor 18. Timer motor 24 drives the cams in the direction indicated by the arrows thereon and commences to accumulate the maximum length of time that motor 18 will be energized.

After the elapse of a predetermined length of time from the time the timer and drive motor are energized, cam 30 permits switch S1 to close on contact 28, thus establishing a holding circuit for timer motor 24 that will retain it energized until switch S1 is again moved into engagement with contact 26.

After switch S1 has moved into engagement with contact 28, switch S2 is actuated by cam 36 to move into engagement with contact 22. This last-mentioned movement of switch S2 de-energizes drive motor 18, thereby halting operation of the refrigeration unit and energizing heating element 16 to initiate a defrosting cycle for the refrigerator.

After a predetermined timed period, determined by the arcuate extent of recess 38 of cam 36, switch S2 is returned to its original position, thereby de-energizing heating element 16 and again establishing the energizing circuit for drive motor 18 to element 20. Normally, element 20 will at this time be open and drive motor 18 will not again become energized.

Shortly after switch S2 is returned to its original position by cam 36, cam 30 returns switch S1 to its original position in engagement with contact 36. At this time, inasmuch as element 20 is open, timer motor 24 will be de-energized and will halt in the position in which it started.

This completes a cycle of refrigeration and defrosting and leaves the evaporator free of frost and ice and in efficient condition for further refrigeration. At any time that element 20 again indicates the need of operation of the refrigeration unit, the above cycle will be repeated. The evaporator will therefore be maintained in a defrosted condition substantially all of the time.

It will be apparent that the timed period of operation of drive motor 18 may vary, and that it may be desirable to interrupt its operation at varying points during the said timed period, and under these circumstances, substantially the same cycle of operations may be obtained by merely lengthening recess 32 of cam 30 so as to be certain of establishing the holding circuit for the timer motor 24 prior to the de-energization of drive motor 18. In any case there will be successive periods of operation of drive motor 18 and heating element 16.

It will also be evident that it may at times and under certain circumstances be desirable first to operate heating element 16, and thereafter to initiate operation of the refrigeration unit by energizing motor 18. This, of course, could readily be accomplished merely by interchanging the positions of drive motor 18 and heating element 16 in the circuit shown in Figure 2, with the provision of any suitable control means for the said motor in addition to the timer control thereof, if further desirable or necessary.

It will be understood that this invention is susceptible to modification in order to adapt it to different usages and conditions, and, accordingly, it is desired to comprehend such modifications within this invention as may fall within the scope of the appended claims.

We claim:

1. In a refrigeration system; a refrigeration unit having a drive motor, a defrosting heater, a switch having a first position for establishing a circuit through said drive motor and a second position for establishing a circuit through said heater, a thermostat in the circuit between said switch and motor responsive to a predetermined temperature in the zone being refrigerated to complete the circuit from the switch to the motor, a timer in parallel with said motor so as to be energized simultaneously therewith and having a cam operable after a predetermined period of energization of said timer to move said switch from its first to its second position for a predetermined timed period, and circuit control mechanism actuated by said timer operable automatically to maintain said timer energized during said timed period and to de-energize said timer at the expiration of said timed period.

2. In a refrigeration system; a refrigeration unit having a drive motor, a defrosting heater, a switch having a first position for establishing a

circuit through said drive motor and a second position for establishing a circuit through said heater, a thermostat in the circuit between said first switch and motor responsive to a predetermined temperature in the zone being refrigerated to complete the circuit from the switch to the motor, a timer in parallel with said motor so as to be energized simultaneously therewith and having a first cam operable after a predetermined period of energization of said timer in operable engagement with said switch to move it from its first to its second position for a timed period, and means operable automatically to maintain said timer energized during said timed period, said 10 means comprising a second switch connected to bypass said first-mentioned switch and thermostat, and a second timer cam in operable engagement with said second switch to move it into closed position prior to the initiation of said timed period and into open position after the expiration of said timed period.

3. In a refrigerator having a refrigeration unit, a drive motor for said unit, a defrosting heater, a timer and a thermostat, an electric circuit therefor, said thermostat being operative at a predetermined temperature in the enclosure being refrigerated to energize said motor and timer, and a circuit control mechanism actuated by said timer operable to de-energize said drive motor after a predetermined total period of time of energization thereof and to simultaneously energize said heater.

4. In a refrigerator having a refrigeration unit, a drive motor for said unit, a defrosting heater, a timer and a thermostat, an electric control circuit therefor, said thermostat being operative at a predetermined temperature in the enclosure being refrigerated to energize said drive motor and timer, and a circuit control mechanism actuated by said timer operable to de-energize said drive motor after a predetermined total period of time of energization thereof, and to energize said heater for a predetermined time period, said mechanism being thereafter operable to automatically de-energize said timer after the expiration of the predetermined period of energization of said heater.

5. In a refrigerator having a refrigeration unit, a drive motor therefor, a defrosting heater, a timer, and a thermostat, a control circuit therefor, said thermostat being operative at a predetermined temperature in the enclosure being refrigerated to energize said drive motor and timer, a switch having a first position wherein said drive motor is energized and a second position wherein said heater is energized, and a circuit control mechanism actuated by said timer operative after a predetermined total time period of energization of said drive motor to move said switch into its second position and after a predetermined further total time period to return said switch to its first position, said mechanism being thereafter operable to automatically de-energize said timer after said switch has returned to its first position.

6. In a refrigerator having an evaporator, a refrigeration unit for supply refrigerant to said evaporator and including a drive motor, an electric circuit connected with said motor, an electric heater in said circuit mounted on said evaporator energizable to defrost the evaporator, a thermostat in said circuit operable to energize said drive motor in response to a predetermined temperature in the zone being refrigerated, a timer connected in said circuit to be energized simul-

taneously with said drive motor, and a circuit control mechanism actuated by said timer after a predetermined period of energization thereof to de-energize said drive motor and energize said heater for a further predetermined period of time and thereafter to de-energize said heater and timer.
